CLAIM

The ornamental design for an injection device as shown and described.

DESCRIPTION

FIG. 1 is an isometric view of our ornamental design of an injection device.

FIG. 2 is a front elevational view of the injection device of FIG. 1.

FIG. 3 is a rear elevational view of the injection device of FIGS. 1 and 2.

FIG. 4 is a left side elevational view of the injection device of FIGS. 1-3.

FIG. 5 is a right side elevational view of the injection device of FIGS. 1-4.

FIG. 6 is a top plan view of the injection device of FIGS. 1-5; and,

FIG. 7 is a bottom view of the injection device of FIGS. 1-6. The broken lines in the drawings illustrate portions of the injection device and form no part of the claimed design.

1 Claim, 6 Drawing Sheets
